(57) **CLAIM**

The ornamental design for a charger adapter, as shown and described.

DESCRIPTION

Reference is made to a related patent application Ser. No. 29/154,508, filed Jan. 28, 2002, U.S. Pat. No. Des. 469,400. FIG. 1 is a perspective view of a charger adapter showing a new design having prongs in the retracted position; FIG. 2 is a front elevational view thereof; FIG. 3 is a top plan view thereof; FIG. 4 is a rear elevational view thereof; FIG. 5 is a bottom plan view thereof; FIG. 6 is another front perspective view showing the prongs in a substantially horizontal position; and, FIG. 7 is a further front perspective view thereof showing the prongs in a substantially vertically extended position.
